DESIGN FOR A SEWING CABINET

**Edwin Boutton and Harry A. Brunner,
Cincinnati, Ohio**

Application October 30, 1933. Serial No. 49,610

Term of patent 3½ years

To all whom it may concern:

Be it known that we, **EDWIN BOUTTON** and **HARRY A. BRUNNER**, citizens of the United States, residing at Cincinnati, in the county of Hamilton and State of Ohio, have invented a new, original, and ornamental Design for Sewing Cabinets, of which the following is a specification, reference being had to the accompanying drawing, forming part thereof in which:

Fig. 1 is a front elevation of a sewing cabinet, showing our new design.

Fig. 2 is an end view thereof, and,

Fig. 3 is a perspective view.

We claim:

The ornamental design for a sewing cabinet, as shown.

**EDWIN BOUTTON.
HARRY A. BRUNNER.**
